UNITED STATES PATENT OFFICE.

PAUL E. HASS, OF NEW YORK, N. Y.

DESIGN FOR A BANK-CHECK.

42,750.

Specification for Design.

Patented July 9, 1912.

Application filed May 2, 1912. Serial No. 694,736. Term of patent 14 years.

To all whom it may concern:

Be it known that I, PAUL E. HASS, a citizen of the United States, and a resident of the city of New York, borough of Manhattan, in the county and State of New York, have invented a new, original, and ornamental Design for Bank-Checks, of which the following is a specification, reference being had to the accompanying drawing, forming a part thereof.

The figure is a plan view of a bank check showing my new design.

I claim:

The ornamental design for a bank check, as shown.

PAUL E. HASS.
